(57) **CLAIM**

The ornamental design for a case as shown and described.

DESCRIPTION

FIG. 1 is a top side view of a case with the lid closed showing the new design;

FIG. 2 is a bottom elevation view thereof;

FIG. 3 is a left side elevation view thereof;

FIG. 4 is a right side elevation view thereof;

FIG. 5 is a front elevation view thereof;

FIG. 6 is a back elevation view thereof;

FIG. 7 is a top down left side perspective view thereof;

FIG. 8 is a top down left side perspective view of the case with the lid open;

FIG. 9 is a top plan view of the case, shown separately to show aspects of the design that are not visible when combined, shown with ear plugs;

FIG. 10 is a top plan view of the case shown with the lid closed, shown in a tray;

FIG. 11 is a bottom elevation view thereof;

FIG. 12 is a left side elevation view thereof;

FIG. 13 is a right side elevation view thereof;

FIG. 14 is a front elevation view thereof;

FIG. 15 is a back elevation view thereof;

FIG. 16 is a top down left side perspective view thereof;

FIG. 17 is a top down left side perspective view of the case shown with the lid closed, shown in a tray with earplugs; and,

FIG. 18 is an exploded view of the case shown in a tray. The broken lines showing the tray and earplugs are for the purpose of illustrating an environment of the article and form no part of the claimed design.

The thin, black lines show contour of the surfaces and curved edges of the case, and are not actual lines on the case.
